UNITED STATES PATENT OFFICE.

FREDERICK W. BAUMANN, OF PITTSBURGH, PENNSYLVANIA, ASSIGNOR TO OLIVER IRON & STEEL CORPORATION, OF PITTSBURGH, PENNSYLVANIA, A CORPORATION OF PENNSYLVANIA.

BENDING MACHINE.

Application filed December 15, 1923. Serial No. 680,949.

To all whom it may concern:

Be it known that I, FREDERICK W. BAUMANN, a citizen of the United States, and resident of Pittsburgh, in the county of Allegheny and State of Pennsylvania, have invented a new and useful Improvement in a Bending Machine; and I do hereby declare the following to be a full, clear, and exact description thereof.

10 My invention relates to a machine for bending metal, and more especially to a machine for bending articles so shaped that it is impossible to withdraw the upper die vertically due to the overlapping of portions of the article, which thereby prevents the vertical withdrawal of the upper die.

The object of my invention is to provide a bending machine of this character which is simple and effective in operation, 20 and in which the upper die is withdrawn in such a manner as not to be interfered with by the article formed thereby.

To these ends my invention comprises the novel features hereinafter set forth and 25 claimed:

In the accompanying drawings Figure 1 is a side elevation partly in section of my improved machine; Fig. 2 is a vertical cross-section of the dies, and connections thereto 30 for operating same, showing the position of the metal on the lower die before the bending takes place in full lines; Fig. 3 is a like view showing the completion of the article before the withdrawal of the upper die; Fig. 35 4 is a cross-section broken away at right angles to Fig. 3; and Fig. 5 is a like view showing the upper die withdrawn.

In the drawings the numeral 2 designates a suitable frame or housing in which is journaled the shaft 3 which carries the large gear 4 driven by the pinion 5, which in turn is driven by a suitable motor.

A crank 6 is mounted on the shaft 3 and the stub-shaft 7. The crank-arm 8 is connected to the crank 6 and to the clevis-member 9. Toggle-arms 10 and 11 are pivotally connected by the pin 12 to the clevis-member 9, said toggle-arms for purposes of adjustment being made in the form of turn-buckles.

45 In order to retain the toggle-arms 10 and 11 in proper position against lateral movement, I provide the stay-rod 10^a which is connected to the clevis 9, and at its outer end is pivotally mounted on the bracket 10^b.

50 The upper ends of the toggle-arms 10 and

11 are pivotally connected to the lugs 13 and 14, respectively, said lugs being connected to the die-holders 15 and 16, respectively. These die-holders have the lugs 17 which are pivotally connected at 18 to the frame.

The die-holders 15 and 16 carry the dies 19 and 20, respectively, said dies being held in the holders by screws 21. By this arrangement dies of different shape or size 65 may be used in said die-holders. For making the particular article here illustrated the dies 19 and 20 are L-shaped, the inwardly projecting portions being grooved as at 21^a so as to partially enclose the article 70 being formed for the reason hereinafter set forth.

The lower die 22 is carried by the cross-head 23, said cross-head being connected by bolts 24 with the sliding-frame 25 which moves up and down in suitable guides 25^a in the housing. The upward movement of the lower die is accomplished by the cams 26 on the shaft 3 and stub-shaft 7, said cams engaging the rollers 27 on the sliding-frame. The cams 26 have the delay 80 faces 28 which provide for holding the lower die in its stationary position during the forming of the article.

The lower die 22 is secured to the cross-head 23 by screw-bolts, so that said lower die may be changed as desired according to the shape of the article to be formed. The lower dies are also grooved as at 30 to hold the article against lateral movement when 90 the upper die is withdrawn, as will more fully hereinafter appear.

The upper die 31 is movable horizontally, and said upper die is connected to the slide-bar 32, said slide-bar having the enlarged 95 portion 33 with a dovetailed seat 34 formed therein to receive said die, which is then secured in place by the key 35. The upper die has the outwardly extending lip portions 36 over which the metal of the article 100 to be formed is bent by the dies 19 and 20, as will more fully hereinafter appear.

The inner end of the slide-bar 32 has the link 37 pivotally connected thereto and to the bell-crank 38 pivotally mounted on the 105 bracket 39 secured to the housing. A link 40 connected to the crank 38 is also connected to the vertical slide-bar 41 moving in suitable guides in the bracket 39. At the lower end of said slide-bar is the roller 42 110

which is engaged by the cam 43 on the shaft 3. To provide for the return of the slide-bar 32, the spring 44 is interposed between the frame 2 and an abutment on the bar 32, said spring being mounted on the rod 46 upon which said abutment is adapted to slide.

In the operation of the machine in making an anti-creeper for railroad-rails, a piece of metal 45 from which the anti-creeper is to be formed is placed upon the lower die in the position indicated in Fig. 2, whereupon the power is applied to rotate the shaft 3, and the cams 26 raise the slide 25, while at the same time the crank 6 raises the toggle-arms 10 and 11. However, the cams 26 are so constructed that the lower die 22 will be advanced to bring the metal 45 into engagement with the upper die 31 before the dies 19 and 20 come into engagement with the upper die, and consequently the metal will be first bent into the shape shown in dotted lines, Fig. 2, with the upwardly extending end portions 46. When the lower die has been raised into this position, the crank 6 has in the meantime been raising the toggle-arms 10 and 11, and the movement of said arms is timed so that the dies 19 and 20 will move in and engage the upwardly extending end portions 46 of the metal, and the said dies will act to bend the metal over on to the lip portions 36 of the upper die as indicated in Fig. 3. Owing to the grooves 21^a in dies 19 and 20 and the groove 30 in the lower die 22, the anti-creeper so formed is held against lateral movement. It is now necessary to withdraw the upper die 31, and this is accomplished by cam 43 which is so timed that it will now act to raise the bar 41, and through the bell-crank 38 the bar 32 will be withdrawn to the left, Fig. 1, and the upper die attached thereto will likewise be withdrawn in a horizontal plane, moving out of engagement with the anti-creeper still held in the lower die 22 and the dies 19 and 20. The operations are so timed that as the upper die is withdrawn in this manner, the toggle-arms 10 and 11 are lowered, withdrawing the dies 19 and 20, leaving the anti-creeper resting on the top die, whence it can be readily removed while the top die is lowered to position to receive another blank.

It will be understood that the dies may

be changed for making many different articles where the ends of the metal are bent inwardly preventing the vertical withdrawal of the upper die, and that changes and modifications may be made in the construction of the machine without affecting the broad scope of the invention.

What I claim is:

1. In a metal bending machine, the combination with a suitable frame, of a shaft, a crank on said shaft, a vertically movable lower die, connections between said shaft and said die for operating the same, a horizontally movable upper die, swinging dies adapted to bend the metal around said upper die, toggle-arms connected to said last-named dies, and a crank-arm on said crank connected to said toggle-arms.

2. In a metal bending machine, the combination with a suitable frame, of a shaft, a crank on said shaft, a vertically movable lower die, connections between said shaft and said lower die for moving the same, a horizontally movable upper die, swinging dies adapted to bend the metal around said upper die, toggle-arms connected to said last-named dies, a crank-arm on said crank connected to said toggle-arms, a stray-rod connected to said toggle-arms, and a stationary support for the outer end of said rod.

3. In a bending machine, the combination with a suitable frame, of a shaft, a vertically movable lower die, an upper die, dies adapted to bend metal around said upper die, a horizontally movable spring-actuated member carrying said upper die, and connections between said shaft and said member for withdrawing said upper die.

4. In a metal bending machine, the combination with a suitable frame, of a shaft, a vertically movable lower die, an upper die, dies adapted to bend the metal around said upper die, a spring-actuated horizontally movable member carrying said upper die, a bell-crank connected to said member, a bar connected to said bell-crank, and a cam on said shaft adapted to engage said bar.

In testimony whereof I, the said FREDERICK W. BAUMANN, have hereunto set my hand.

FREDERICK W. BAUMANN.
